BOOT HANGER

Clifford C. Haumerson, Janesville, Wis.

Application September 13, 1933, Serial No. 689,177

6 Claims. (Cl. 12—123)

My invention relates to devices for holding and suspending rubber boots in a manner as to permit the inside of the boot to dry readily and, in the instance of rubber hip boots, to prevent the boot from breaking at the point where the flexible thigh coverage is joined to the stiffer calf covering portion of the said boot.

The upper or thigh covering portion of most of the boots manufactured today is flexible to permit the said flexible portion to be folded down over the stiffer portion in the form of a cuff in order to facilitate the putting on and removal of the boot and to support the upper flexible portion when the boot is not in use. Furthermore, the said flexible portion is cuffed about the top edge of the stiff portion when the user desires to protect only the calf portion of his legs.

When the boots are not in use, the owner usually cuffs the top flexible portion in order to prevent the said flexible portion from drooping onto the floor. This cuffing of the flexible portion, as above stated, causes the boot to crack in the folds of the cuff.

My device permits of the storing of boots in an inverted position as to allow the flexible portion to be fully extended and thus prevent cracking of the boot due to the folds necessary in forming a cuff.

Another object the use of my device accomplishes is that due to the fact that boots may be suspended in inverse position, the said boots may be readily hung over a stove and the heat reflected therefrom will quickly dry the inside thereof.

In order to fully understand my invention, reference should be had to the accompanying drawing in which:

Fig. 1 is a perspective view of one of my boot holding devices;

Fig. 2 is a side plan view showing the boot positioned within the holder; and

Fig. 3 is a detailed view disclosing a method of affixing the spanner member to one of the wedge plates.

In the drawing the numeral 10 will hereinafter be used to designate a spanner member which is made of stiff bronze wire approximately an eighth of an inch in diameter, the ends of which are bent downwardly to receive wedge plates and the middle bowed to provide a seat for a hook 11, the lower end of which is bent upon itself to prevent separation of the hook from the spanner member, the upper end being bent in a half radius to provide means for readily suspending the assembled device. To the opposed downwardly

bent ends of the spanner member are attached clamping plates 12 and 13. The said plates are of metal and the upper edges are bent outwardly at approximately right angles and drilled as at 14 and 15 to receive the downwardly bent ends of the spanner member.

Flanges 16 and 17 are formed in the side of the wedge plates, the operation of forming the said flanges consisting of perforating the metal with a U-shaped punch, forcing the tongues so formed outwardly to an angle of 90 degrees from the outer face of the wedge member and drilling the said bent-out flange as to take the ends of the spanner member.

It is to be noted that the perforations 14 and 15 in the flange formed by bending the top edge of the wedge members outwardly and the perforations in the flanges 16 and 17 are aligned so that when the wedge members are affixed to the downwardly bent ends of the spanner member and the extremities of the said spanner member are crimped, the wedge plates will be so fixed to the spanner member as to permit limited rotation of the said plates, the limitation being contact of the wedge plates one against the other when one or both are rotated. This rotatability of the said wedge plates permits of the rotation of each in the same direction as to place the inside surfaces of the plates in contact with each other, thus allowing the assembled device to be packed flat.

It is to be further noted that the lower edges of the plates are formed in a convolute curve and the angle of the bend of the ends of the spanner member is such that when the wedge plates are affixed to the said ends, the said plates taper towards each other from top to bottom as to permit wedging of the inverted last portion of a boot between the two plates, allowing the upper portion of the boot to extend downwardly between the bottom edges of the wedge plates.

The device functions as follows:

The boot to be suspended is inverted, the heel is inserted between two opposed wedge plates. The boot is then forced inwardly between the said plates until the plates clamp said boot approximately midway of the toe and heel, whereupon the user may hang the boot in a desirable place, preferably some distance from the floor as to permit the suspended cuff to clear the said floor.

Having described my invention, what I claim and desire to secure by Letters Patent is:

1. A boot hanger comprising in combination a spanner member and relatively rotatable clamp-

ing members mounted upon the extremities of said spanner member.

2. A boot hanger comprising in combination a spanner member, the extremities of which are bent downwardly, relatively rotatable wedge plates mounted upon the said downwardly bent extremities.

5 3. A boot hanger comprising in combination a spanner member, the extremities of which are bent downwardly, wedge plates having limited 10 rotatable movement mounted upon the said downwardly bent extremities of the said spanner member.

15 4. A boot hanger comprising in combination a spanner member, the extremities of which are bent downwardly, wedge plates having a limited rotatable movement mounted upon the said downwardly bent extremities of the said spanner member, the said plates being formed in a convolute 20 curve in their face and being fixed on the extremities of the spanner member in a manner as to cause the face of the said plates to taper inwardly from top to bottom.

25 5. A boot hanger comprising a resilient substantially U-shaped spanner member having downwardly extending converging leg portions, and a pair of elongated clamping plates rotatably

mounted upon the leg portions of said spanner member, the rotatable mounting of said plates providing for the movement of said plates to an operative position at right angles to said spanner member with the plates in opposed spaced parallel relation to define a boot receiving opening diminished in width toward the lower edges of the plates or to an inoperative position substantially parallel with said spanner member with the plates in contact with each other.

5 6. A boot hanger comprising a resilient substantially U-shaped spanner member having downwardly extending converging leg portions, and a pair of elongated plates located between and rotatably mounted intermediate the ends 15 thereof upon the legs of said U-shaped spanner member, the rotatable mounting of said plates providing for the movement of said plates to an operative position at right angles to said spanner member with the plates in opposed spaced parallel relation to define a boot receiving opening diminished in width toward the lower edges of the plates or to an inoperative position substantially parallel with said spanner member with the plates in contact with each other.

10 20 25 CLIFFORD C. HAUMERSON.
